UNITED STATES PATENT OFFICE

ANDREW A. KUCHER, OF CHESTER, PENNSYLVANIA, ASSIGNOR TO WESTINGHOUSE ELECTRIC & MANUFACTURING COMPANY, A CORPORATION OF PENNSYLVANIA

REFRIGERATOR-MOTOR-LUBRICATING SYSTEM

Application filed October 13, 1925, Serial No. 62,275. Renewed January 21, 1928.

My invention relates to the lubrication of electric motors and particularly to those motors which are employed for driving the compression mechanisms of small capacity refrigerating machines such as are suitable for household use and it has for an object to provide a novel method and means for effectively lubricating the working parts of such motors continuously and reliably for extended periods of time without care or attention. It has for a further object to provide adequate means for confining the lubricant to the bearings and the working parts of the motor exclusively and for preventing leakage of the lubricant upon the current bearing portions of the motor.

These and other objects, which will be made apparent throughout the further description of my invention, may be attained by the employment of the apparatus hereinafter described and illustrated in the accompanying drawing in which the single figure is a view, in sectional elevation, showing a refrigerating machine of the compression type in which the motor lubricating system is arranged in accordance with my invention.

Compression refrigerators normally comprise a chamber in which a working fluid is evaporated at a relatively low pressure and temperature, a chamber in which the vapors are condensed at a high pressure and temperature, a compression mechanism for translating the vapors from the evaporating chamber to the condensing chamber, and a valved conduit for returning the condensed fluid at a reduced pressure into the evaporation chamber.

The compression mechanism, consisting essentially of a motor and a compressor, is preferably housed within a single fluid tight chamber, as such an arrangement avoids the use of a stuffing box between the compressor and the motor, prevents leakage of the refrigerating fluid, insures quiet operation, and provides a very compact organization. With the motor totally enclosed in this manner, some means for lubricating it must be provided which will operate without attention continuously and reliably for long periods of time as, for example, one to two years.

This problem of lubricating the working parts of an enclosed refrigerator motor is especially difficult where motors of the commutator type are employed and where the depositing of only a small amount of lubricant upon the current bearing portions of the motor may bring about flashing and attendant pitting, also deterioration of the insulation. It is to this problem of effectively lubricating the working parts of enclosed refrigeration motors that the present invention specifically relates.

Referring to the drawing for a description of my invention, I show the condensing chamber of a compression refrigerating machine of the type disclosed in a copending application of mine, serially numbered 509,672, filed October 22, 1921 and entitled "Refrigeration machine" and in which my novel method of lubrication may be carried out. It is to be understood that this invention may be practiced in other types of compression machines and that the apparatus illustrated and herein described is employed by way of example and as an aid in presenting a clear exposition of my invention. As illustrated, 10 designates a condensing chamber. A compressor 11 driven by a suitable motor 12 is disposed within the chamber. The condensing chamber 10 comprises a bell or dome, 13, secured to a base plate 14 as by bolts 15. Supported upon the base plate 14 is an inverted cup-shaped casting 16 forming a housing for the motor, and super-imposed thereon is a receptacle 17 which houses the compressor 11 and serves as a collection chamber for the liquid working fluid discharged by the compressor. Suspended from the base plate 14 is a removable cup-shaped casting 18 for permitting renewal of the commutator brushes associated with the motor.

The motor shaft 21 is secured to the compressor shaft 22 by a suitable key 23 thus producing, in effect, a common shaft. This shaft is supported by a lower bearing 24 provided in the casting 18, an intermediate bearing 25 provided in the upper portion of the casting 16 and an upper bearing 26 provided in the compressor. The compressor is provided with an inlet port 28 and a discharge

port 29, the latter communicating with a conduit 35 having an open end 36 supporting a baffle 37 for separating the mixed liquid working fluid and vapor discharged from the compressor. The receptacle 17 communicates with the condensing chamber 10 through an outlet 38 provided in its upper portion for the passage of refrigerant vapor and through an opening 39 for permitting excess liquid working fluid to overflow.

Condensing coils 40 are arranged in the upper part of the dome 13 which are provided with an inlet connection 41 and an outlet connection (not shown) which pass without the chamber. The condensed fluid is conveyed to one or more evaporators 43 by a conduit 44, the flow through the conduit 44 being controlled by a float valve 45 in order that a constant body of liquid may be maintained in the condensing chamber. Refrigerant vapor is removed from the evaporator 43 by a conduit 46 and conveyed to a surge tank 47 containing a body of liquid refrigerant having a level such as indicated at 48. The conduit 46 is so arranged with respect to the surge tank that it communicates with the surge tank at a point below the liquid level 48. The surge tank 47 may be of circular conformation and has disposed therein inner and outer concentric cups 50 and 50' which may be supported upon the conduit 44 and which have their upper portions extending above the level of the liquid 48. Provided in the inner cup 50 is a small opening or aperture 49 while provided in the outer portion of the cup 50' is a plurality of relatively large circumferentially spaced openings 51. The inner and outer cups 50 and 50' define, what may be termed, a tranquil chamber 52 whereby the flow of liquid through the small aperture 49 is not influenced by the turbulence of the liquid contained in the main body of the surge tank 47. Extending downwardly from the upper portion of the surge tank and concentrically disposed between the conduit 44 and the cup 50 is an outlet conduit 53 having its entrant portion located at 54 for conveying refrigerant vapor from the surge tank 47 to a passage 55 communicating with the suction port 28 of the compressor. An electric cable 56 for furnishing current to the motor passes through a fluid tight plug 57 provided in the base plate 14.

An inverted tube 61 is provided for supplying the upper shaft bearing 26 with lubricant. This tube has an open inlet and has its discharge communicating with a cylindrical passage 62 arranged coaxially with the shaft. A groove 63 conveys the lubricant into the upper bearing 26 and it is discharged at the lower end of the bearing to the compressor. It percolates through the various clearances provided in the working parts of the compressor to the upper surface of the casting 16, and a portion thereof feeds downwardly in a

groove 64 to lubricate the bearing 25. A circular groove 66 is provided in the compressor shaft 22 for trapping lubricant which seeps downwardly between the shaft and the casting. The circular groove 66 communicates through a radially disposed opening 67 and a hollow portion 68 of the compressor shaft with a conduit 69 which extends downwardly into the hollow motor shaft 21.

An oil catcher 71 is secured to a jacket 72 provided on the motor shaft 21 in order to prevent lubricant which may seep past the circular groove 66 from falling upon the armature windings of the motor. The lubricant is drained from the oil catcher 71 by means of an opening 72' and a longitudinal groove 73 which communicates with the bore of the motor shaft 21.

A circular recess 74 is provided in the cup shaped casting 18 for receiving lubricant discharged from the lower end of the motor shaft. The circular recess 74 communicates with an annular opening 75 formed by ball retainer rings 76 and 77 of the bearings 24. It further communicates through an opening 78 with an annular passage 79 which, in turn, is drained by means of a conduit 81. The conduit 81 is connected, as shown, to the upper portion of the surge tank 47 for draining the lubricating fluid thereto. The lower surface of the annular passage 79 is disposed a slight distance below the center line of the balls 82, and a level of lubricant corresponding thereto is consequently maintained about the bearing. This construction provides ample lubrication for the bearing and prevents such an accumulation of lubricant as might possibly interfere with the successful operation of the motor.

In order to further guard against lubricant being carried upwardly along the shaft and coming in contact with the current bearing portions of the motor, I interpose a series of baffles between the motor and the bearing 24. I have found from experiment, that upon a stoppage of the apparatus, the pressure immediately attempts to equalize between the condensing chamber and the motor chamber, thereby causing the fluid to flow in a backward direction through the passage 55 and conduit 53. However, by leading the drain conduit 81 into the surge tank, this back-flow of gas is prevented from spraying lubricant into the motor chamber through the conduit 81 because of the relatively large volume of the surge tank and its capacity to absorb the change in pressure. However, as an added precaution, I may provide a baffle 82' which is snugly fitted in the bore of the casting 18. This baffle extends over the inlet end of the conduit 81 and should any lubricant be possibly sprayed from the conduit 81 it impinges upon this baffle. In addition, I provide a baffle 83 which is rotatable with the shaft and a sleeve 84. This sleeve trans-

mits the weight carried by the shaft mechanism to the ball retainer 76 and also holds the baffle 83 rigidly against a suitable shoulder provided on the motor shaft. Any lubricant which may creep upwardly on the sleeve 84 is carried on to the baffle 83 and is thrown tangentially therefrom by the action of centrifugal force. Communication between the motor and the bearings 24 is still further restricted by a baffle 85 which is fixed in the casting 19 and through which the motor shaft extends, making a close clearance therewith. All of the structure heretofore described for supplying lubricant to the intermediate and lower bearings 24 and 25 and for preventing the lubricant supplied to these bearings from coming into contact with the current bearing portions of the motor, with the exception of arranging the drain conduit 81 so as to communicate with the surge tank 47, is shown in a copending application of mine serially numbered 643,364, filed June 4, 1923 and entitled "Refrigerator."

The operation of the above embodiment of my invention is as follows:—

Upon starting the motor 12, the action of the compressor 11 produces a relatively low or sub-atmospheric pressure within the evaporator 43. The pressure thus produced is sufficiently low to induce vaporization of the liquid refrigerant and heat is absorbed from the surrounding atmosphere through the walls of the evaporator 43, the vapor thus produced passing through the conduit 46 into the surge tank 47. Within the surge tank 47, the vapor rises upwardly and is then drawn downwardly into the cup 50 to the entrant port 54 of the suction conduit 53 from whence it passes upwardly through the passage 55 to the inlet port 28 of the compressor. During the passage of the refrigerant vapor, a small quantity of liquid working fluid drains through the aperture 49 into the interior of the cup 50 and this liquid is entrained in the refrigerant vapor passing to the compressor. In this manner, a constant circulation of the liquid working fluid, which liquid is composed of both a refrigerant and a lubricant, is constantly maintained throughout the evaporator 43 and surge tank 47 and the segregation of the lubricant in the evaporator 43 and the surge tank 47 is prevented. In addition, this liquid in passing through the compressor 11 lubricates and seals the same. The compressor 11 discharges refrigerant vapor removed from the surge tank 47 at an increased pressure through the conduit 35 and causes it to impinge against the baffle 37. In this way, the liquid working fluid which is entrained in the refrigerant vapor is separated therefrom and falls downwardly into the receptacle 17, while the refrigerant vapor passes through the opening 38 into the condensing chamber. The liquid working fluid within the receptacle, being subject to the

heat of the compressor, has its refrigerant component largely vaporized off, leaving a body of liquid containing a high percentage of lubricant. This novel method of producing a fluid for lubricating a refrigerating machine is disclosed in a copending application of mine, serial number 643,364, filed June 4, 1923 and entitled "Refrigerator."

The hot refrigerant vapors after passing through the opening 38, come into contact with the coils 40 and are condensed by the cooling action thereof. The condensed refrigerant falls to the lower portion of the condensing chamber and, upon sufficient rise of liquid level therein, the float valve 45 opens to permit a flow of liquid refrigerant through the conduit 44 directly to the evaporator 43. Any excess lubricating fluid which may accumulate within the receptacle 17 overflows through the outlet 39 and commingles with the condensed refrigerant in the condensing chamber 10 from whence it is conveyed through the conduit 44 to the evaporator 43 and is returned to the compressor 11 in the manner heretofore described.

Lubrication of the working parts of the compression mechanism is accomplished as follows:

The liquid working fluid contained in the receptacle 17, which has been subjected to the heat of the compressor and also to some of the heat of the motor and which therefore contains a high percentage of lubricant, is conveyed to the cylindrical opening 62 by the conduit 61 because the pressure prevailing within the compressor is relatively lower than that of the receptacle 17. The lubricant then feeds downwardly through the working clearances normally provided in a compressor of this character and a considerable portion is deposited upon the upper surface of the motor housing 16. For a more detailed description of the manner in which the lubricant passes through the compressor 11, reference may be had to my copending application, serially numbered 260,487 and entitled Refrigerator compression mechanism. Because of the still lower pressure prevailing within the motor housing, the lubricant readily enters the groove 64 and the bearing 25 after which a considerable portion is trapped within the circular groove 66 and is conveyed through the radial opening 67 to the hollow portion 68 of the compressor shaft from whence it is conveyed into the conduit 69 and thence to the bore of the motor shaft 21.

A small quantity of lubricant may seep past the circular groove 66 and be discharged from the lower end of the bearing. This lubricant will be deposited upon the upper end face of the motor shaft 21 whereupon it will be thrown outward, by the action of centrifugal force, into the lubricant catcher 71. From the lubricant catcher 71 the oil

drains inwardly through the opening 72 and the groove 73 to the bore of the motor shaft 21, the static pressure of the oil accumulating in the catcher 71 being sufficient to compel constant drainage notwithstanding the slight opposing action created by the centrifugal action of the motor shaft 21. By the employment of such apparatus, the possibility of leakage of the lubricant upon the current bearing portions of the motor is made very remote. I have found from experiment that my apparatus may be operated for extended periods of time without any of the lubricant coming into contact with the windings of the motor.

Lubricant discharged from the lower end of the motor shaft passes to the circular recess 74 and to the bearing 24. The lubricant is withdrawn from the bearing through the opening 78 which communicates with the conduit 81. As the level of the annular passage 79 is disposed slightly below the center line of the bearing 24, substantially one half of the bearing 24 is immersed in the lubricant at all times. This level of lubricant is sufficient to insure adequate lubrication of the bearing and is of such relatively small quantity that the possibility of a portion of it traveling upwardly to the windings of the motor is reduced to minimum.

As shown in the drawing, the conduit 81 is connected to the surge tank 47 and lubricant removed from the lower bearing 24 drains into the surge tank 47 and is returned to the inlet of the compressor by way of the aperture 49. The connection of the conduit 81 to the surge tank possesses numerous advantages in that machines of the household type are generally operated intermittently and that upon a stoppage of the machine there is an immediate tendency for the pressure in the condensing chamber and in the evaporator to equalize. In other words, there is a rush of pressure through the compressor 12 and its suction passage 55 into the surge tank 47 which, because of its relatively large volume, readily dampens this rush of pressure and prevents the lubricant which may be contained in the conduit 81 from being sprayed back into the motor chamber and over the motor. In addition, during the idle period of the machine, there is a gradual leakage of lubricant from the receptacle 17 downwardly into the working parts of the compressor and the intermediate bearing 25 to the lower bearing 24. In my arrangement this lubricant is drained into the conduit 81 and collects in the surge tank and not in the motor housing 16. Upon the machine resuming operation, the compressor 11 returns this lubricant to the receptacle 17.

From the foregoing it will be apparent that I have devised a novel method and means for adequately lubricating the working parts 65 of the motor of a refrigerating machine in

which the motor is totally enclosed in a common fluid tight chamber with the compressor. My entire system of lubrication has been so arranged that leakage of the lubricant upon the current bearing portions of the motor is positively prevented, while accumulation of lubricant in the motor housing is also avoided. One very important feature of my invention resides in the fact that I maintain the discharge pressure of the compressor in the lubricant receptacle while I maintain the suction pressure of the compressor in the motor housing and that I utilize this difference in pressure to compel the lubricant to pass through and to thoroughly lubricate the entire working parts of the motor.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a lubricating system for an intermittently operated fluid translating apparatus, the combination of a compressor, a receptacle for containing lubricant, means for repeatedly conveying lubricant from the receptacle to the compressor and back to the receptacle during the active periods of the compressor and for removing lubricant from the receptacle during at least portions of the inactive periods of said compressor, and a chamber for collecting the lubricant removed from the receptacle during the inactive periods of said compressor.

2. In a lubricating system for an intermittently operated fluid translating apparatus, the combination of a compressor, a receptacle for containing lubricant, means motivated by the operation of the compressor for conveying lubricant from the receptacle to the compressor and thence back to the receptacle during the active periods of the compressor and for removing lubricant from the receptacle during at least portions of the inactive periods of the compressor, a second receptacle for collecting the lubricant removed from the first receptacle during inactive periods of the compressor, and means for returning the collected lubricant in the second receptacle to the first receptacle.

3. In a lubricating system for an intermittently operated refrigerating apparatus, the combination of a condensing chamber, a compression mechanism disposed within the condensing chamber, a receptacle for supplying lubricant to the working parts of the compression mechanism during the operation of the machine, and a chamber associated with the compression mechanism for collecting the

lubricant from the receptacle during the idle periods of the machine.

4. In a lubricating system for an intermittently operated refrigerating apparatus, the combination of a condenser, a compressor disposed within the condenser, a motor disposed below the compressor for driving the same, a receptacle disposed about the compressor for supplying lubricant to the working parts of the compressor and the motor during the operation of the machine, and a reservoir for collecting the lubricant from the receptacle during the idle periods of the machine.

5. In a lubricating system for an intermittently operated refrigerating apparatus, the combination of a motor including a housing, a compressor driven by the motor and superimposed upon the motor housing, a receptacle surrounding the compressor and containing a supply of lubricant for the compressor and the motor during the operation of the machine, and a reservoir for containing the lubricant during the idle periods of the machine.

6. In a lubricating system for an intermittently operated refrigerating apparatus, the combination of a motor including a housing, a compressor driven by the motor and superimposed upon the motor housing, a receptacle surrounding the compressor and containing a supply of lubricant during the operation of the machine, and a reservoir for collecting the lubricant during the idle periods of the machine, said reservoir having a capacity equal to or greater than the capacity of the lubricant receptacle.

7. In a lubricating system for an intermittently operated refrigerating apparatus, the combination of a compressor, a motor for driving the compressor, an evaporator, communicating means provided between the evaporator and the inlet of the compressor, a chamber adapted to collect lubricant provided in said communicating means, and a drainage connection provided between said chamber and the motor.

8. In a lubricating system, the combination of a motor, a compartment, a compressor for removing vapor from the compartment, means for supplying lubricant to the working parts of the motor, means for draining lubricant from the motor to the compartment, and means provided in the compartment for entraining the lubricant in the refrigerant vapor passing to the compressor.

9. In a lubricating system, the combination of a compressor, a motor for driving the compressor, a receptacle, means for maintaining a body of lubricant under pressure in the receptacle, means subject to the pressure within the receptacle for delivering lubricant to the working parts of the motor, means for utilizing the compressor to return the lubricant to the receptacle, and a surge tank interposed in said return means, whereby upon

a stoppage of the motor and a consequent return flow of fluid pressure from the receptacle through the compressor toward the motor, lubricant contained in the return means is supplied to the surge tank and not to the motor.

10. In a lubricating system, the combination of a motor, a fluid tight housing for the motor, a compressor driven by the motor, a receptacle containing lubricant and subject to the discharge pressure of the compressor, communicating means provided between the inlet of the compressor and the motor housing for removing lubricant therefrom, means subject to the difference in pressure between the inlet and the discharge of the compressor for conveying lubricant to the working parts of the motor, and a surge tank of substantial capacity located in the communicating means provided between the motor housing and the inlet of the compressor.

11. In a lubricating system for an intermittently operated refrigerating apparatus, the combination of a motor, a compressor driven by the motor, a receptacle containing a supply of lubricant for the compressor and the motor during the operation of the machine, and a reservoir for containing the lubricant during the idle periods of the machine.

12. In a lubricating system for an intermittently operated fluid translating apparatus, the combination of a compressor, a receptacle for containing lubricant, means responsive to the operation of the compressor for circulating lubricant from the receptacle to the compressor and thence back to the receptacle during active periods of the compressor, means motivated by the pressures resulting from the operation of the compressor for removing lubricant from the receptacle during at least portions of the inactive periods of said compressor, and a second receptacle for collecting the lubricant removed from the first receptacle during the inactive periods of said compressor.

13. In a lubricating system for an intermittently operated fluid translating apparatus, the combination of a compression mechanism, a receptacle for supplying lubricant to the compression mechanism during the active periods of the same as well as subsequent thereto, a reservoir for retaining the lubricant discharged from the compression mechanism during the inactive periods of the same, and means for returning lubricant from the reservoir to the receptacle during active periods of the compression mechanism.

In testimony whereof, I have hereunto subscribed my name this 7th day of October, 1925.

ANDREW A. KUCHER.
